UNITED STATES PATENT OFFICE.

ELON HUNTINGTON, OF NEW YORK, N. Y.

DESIGN FOR CANISTERS FOR TEAS, COFFEES, &c.

Specification forming part of Design No. 7,097, dated January 6, 1874; application filed December 23, 1873.
[Term of Patent 3½ years.]

To all whom it may concern:

Be it known that I, ELON HUNTINGTON, of the city and State of New York, have invented a new and original Design for a Canister for Teas, Coffees, &c., of which the following is a description:

Canisters have been made in which the cover or lid is curved both inwardly and outwardly, and the fronts of such canisters have been made as ogees or compound curves, and in some cases the sheet metal at the side portions of the front has been inclined or beveled. I do not lay claim to any of these configurations.

The design of the present shape and configuration is made with reference to improving the ornamental appearance of the front of the canisters by angular buttresses at each side of the rounding front, so that upon the flat surfaces of these angular buttresses there may be different ornamental colors or figures painted, and when these canisters are placed in a row these angular buttresses have a very handsome appearance.

In the drawing, Figure 1 is a perspective view of the canister, and Fig. 2 is a sectional plan of the same.

The sides *a*, back *b*, top *c*, and lid *d*, are of usual shape, and the front is made of the cylindrical segment *e* and angular buttresses *ff*, such angular buttresses being of a V form, as represented, the angle being about ninety degrees, and the face contiguous to the sides *a* of the can being about forty-five degrees from the plane of said sides.

I claim—

The design of the ornamental shape and configuration of the angular buttresses at the sides of the rounding canister front, as described and represented.

Signed by me this 16th day of December, A. D. 1873.

ELON HUNTINGTON.
